CLAIM

The ornamental design for an interlockable bottle cap, as shown and described.

DESCRIPTION

FIG. 1 is a top view of an interlockable bottle cap, showing my design;

FIG. 2 is a front view thereof, the rear view being a mirror image thereof;

FIG. 3 is a right side view thereof, the left side being a mirror image thereof;

FIG. 4 is a bottom view thereof;

FIG. 5 is a top perspective view thereof, shown in a condition of use with other interlockable bottle caps forming no part of the claim; and,

FIG. 6 is a top view thereof.

The broken lines are shown for the purpose of illustrating parts of the interlockable bottle cap that form no part of the claim.

1 Claim, 6 Drawing Sheets
